PLASTIC HEEL GUARD

Edward Lindner and Martha Muller,
Philadelphia, Pa.

Application September 17, 1951, Serial No. 246,930

1 Claim. (Cl. 36—55)

1

Our invention relates to a new and useful plastic heel guard and has for one of its objects to provide a heel guard that may be inserted in a shoe without the use of fastening devices and will remain firmly in place due to its novel form and will prevent chafing of the user's heel and undue wear on the hosiery.

Another object of our invention is to construct a heel guard to be placed in a shoe and comprised of a plastic counter having some resiliency while being sufficiently stiff to retain its form, and a plastic heel tread connected with the counter through the medium of a fabric binder of unique formation.

Another object of this invention is to produce a heel guard including a counter and a heel tread having smooth and lustrous surfaces so that no protuberances are present which might cause chafing of a person's heel or wear on the hosiery.

Another object of the present invention is to provide a heel guard in which the counter is shaped to provide an outwardly projecting bulge at the rear to correspond to the shape of a person's heel and a guide lip at the upper edge whereby a person's foot may be readily and easily slipped into the shoe equipped with such a guard.

Another object of our invention is to provide the outer surface of the fabric binder with a coating of rubber composition to repel moisture and provide a slight frictional resistance between the guard and the shoe in which it is mounted.

With the above and other objects in view this invention consists of the details of construction and combination of elements hereinafter set forth and then designated by the claim.

In order that those skilled in the art to which this invention appertains may understand how to make and use the same we will describe its construction in detail referring by numerals to the accompanying drawing, in which:

Fig. 1 is a side elevation of a plastic heel guard constructed in accordance with our invention.

Fig. 2 is a top plan view thereof.

Fig. 3 is a face view of the blank for the guard counter.

Fig. 4 is a side view of the counter.

Fig. 5 is a face view of the fabric binder blank.

Fig. 6 is a similar view of the plastic tread.

Fig. 7 is a plan view of the tread panel imposed on the binder and prior to the tabs being turned up.

Fig. 8 is a fragmentary sectional view of a shoe with a guard therein also in section.

2

In carrying out our invention as herein embodied 10 represents a fabric binder fashioned to include a heel pad portion 11 of the general shape of the bottom of a person's heel with a pronounced scalloped edge to form tabs 12 extending from the rear portions and the side edges of the heel pad area within the dotted line 12a and the rear edge thereof. These tabs are convexly curved and sufficiently spaced apart so that they will not overlap one another when turned up substantially perpendicular to the heel pad portion 11 of the binder 10.

The exterior surface of the fabric binder, that is the underneath surface of the heel pad portion and the outside surfaces of the tabs as shown in Fig. 1 is coated with a rubber composition represented by the stippling 13, Fig. 1.

A heel tread 14 is produced from a sheet of plastic to provide smooth and lustrous surfaces. 20 This heel tread is substantially the same shape as the bottom of a person's heel and of a size to fit the heel pad portion 11 of the binder 10 within the scalloped edge or tabs 12. Said heel tread 14 is superimposed upon the upper or interior surface of the heel pad portion of the binder and pasted in place by a suitable adhesive 15, represented by the stippling in Figs. 5 and 7.

A guard counter 16 is produced from a sheet 30 of plastic to provide smooth and lustrous surfaces and of sufficient stiffness to retain its shape. It is first blanked out as a substantially semi-circular panel 17, Fig. 3, with the corners rounded as at 18. The blank is then bowed to the 35 shape of the rear periphery of the heel tread 14 and has an outwardly bulged area 19 at the rear finally blending into an outwardly canted guide lip 20 at the upper rear edge and extending for a considerable distance around the inclined sides but terminating short of the base.

At a suitable period during the construction 40 of the heel guard, the tabs 12 are turned or bent upwardly, Fig. 1, and the guard counter 16 is positioned to rest on top of the heel tread 14 contiguous the edge thereof with the rounded corners 18 adjacent the forward edges of the forward tabs and pasted thereto by the adhesive 15 thus completing the heel guard as a unitary article.

50 The heel guard is inserted in the heel portion of a shoe 21, as shown in Fig. 8, and the rubber coated surface contacts the inside of the shoe walls and has a tendency to retain the heel guard in place but is free to move about until it assumes a proper fit within the shoe. Because of

the smooth and lustrous surfaces facing the wearer's heel or stocking chafing or undue wear will be prevented.

The heel guards are produced in various sizes to fit men's, women's and children's shoes and the number of tabs 12 may be varied as desired, it having been discovered that a less number than herein shown may be employed in the larger sized guards.

Of course we do not wish to be limited to the exact details of construction herein shown and described as these may be varied within the scope of the appended claim without departing from the spirit of our invention.

Having described our invention what we claim 15 as new and useful is:

A heel guard, to be inserted in a shoe, consisting of a fabric binder including a heel pad portion of the general shape of the underside of a person's heel and scallop-like tabs upturned 20 from the heel pad portion, a coating of rubber composition on one face thereof, a heel tread of plastic having smooth surfaces and of the same shape as the heel pad portion of said binder, said heel tread being fixed to said heel pad portion by 25 an adhesive composition, and a guard counter produced from a bowed substantially semi-circular panel of plastic having smooth surfaces fitted to and resting on the rear portion of the heel tread contiguous the edge thereof, said guard 30

counter having forwardly and downwardly inclined upper side edges terminating in rounded lower corners and fixed along the base thereof to the inside surfaces of the tabs by the adhesive on the binder, said guard counter also having along its upper marginal region an inwardly turned portion merging with an outwardly bulged outer marginal portion, said portions blending near said lower corners into the guard counter proper, and blending at the upper rear end of said outwardly bulged outer marginal portion into an outwardly projecting canted guide lip around the upper rear edge and upper side edges of said guard counter.

EDWARD LINDNER.
MARTHA MULLER.
